(57) **CLAIM**

The ornamental design for a wall mounted rack, as shown and described.

DESCRIPTION

FIG. 1 is a top plan view of the wall mounted rack of this invention, with the bottom view being a mirror image thereof; FIG. 2 is a top view of the rack of FIG. 1; FIG. 3 is a bottom view of the rack of FIG. 1; FIG. 4 is a right side view of the rack of FIG. 1; FIG. 5 is a left side view of the rack of FIG. 1; FIG. 6 is a bottom perspective view of the rack of FIG. 1; and, FIG. 7 is a front perspective view of the rack of FIG. 1. The area between the broken away lines is understood to describe an area which forms no part of the claimed design.
